HEINRICH FREISE, OF BOCHUM, GERMANY

AEROPLANE WING

Application filed August 5, 1927, Serial No. 210,949, and in Germany August 6, 1926.

My present invention broadly relates to aeroplanes and more particularly to aeroplane-wings and has for its object the provision of an aeroplane-wing adapted to increase the buoyancy of aeroplanes and the like to a degree hitherto not attainable.

To increase the buoyancy of aeroplanes they were until now provided with comparatively thick wings wherein numerous channels, passages, ducts or slits were arranged in an oblique direction to let the air on its upward way therethrough press against the upper surface thereof; or the air was caused to bear in form of natural whirls, or artificially produced whirls, against the underside of the wings; or when the wings were hollow, the air was led through slits arranged in the under-layer of the wing and caused to press against the under surfaces of the upper-layer thereof. The practical results obtained by means of these and similar structures were however very insignificant, since the air pressure under the wing is comparatively small and reaches, broadly spoken, only one third of the air pressure created by the velocity of the aeroplane.

In accordance with my present invention this drawback is removed by means of a novel construction of the wing, wherein in addition of the known underpressure still another underpressure comes into action, which approximately equals the airpressure created by the velocity of the aircraft. To this end the air is introduced into a hollow space of the wing at the frontal edge of the latter and is compressed therein to the extent indicated above. This I accomplish by means of air-inlet-channels kept in parallelism with the direction of the motion of the air and pivotally arranged at the front end of said hollow space of the wing. By means of such air-inlet-channels of sufficiently large cross-sectional area the air can not turn aside but is compelled to flow with little or no resistance through said inlet-channels into the hollow wing. The utilization of this exceptionally high compressed air I accomplish as shown by way of example in the annexed drawing, by leading the air upward through longitudinal slots of the intermediate part

of a flat wing-frame against deflectors which simultaneously cause the formation of many strong air-whirls which press against curved jalouzie blades and the like and are kept by the latter under high pressure on their whole way backward and also laterally. Hereby said whirls are guided in such a manner that after their exit they energetically carry along with them the air which passes over the exposed parts of said jalouzie blades forming the top-layer of the wing and thereby rarefy the air in contact therewith and thus increase the under-pressure considerably. This mode of operation makes my invention also adapted for other surfaces operated upon by a current of a medium, as for instance it is the case by air-ships, wind-power plants, sails of ships, vanes of water-turbines and the like.

In the accompanying drawing one embodiment of my invention is shown by way of example.

Figure 1 is a plan view of an aeroplane provided with the improved wing with parts broken away to show structural details.

Figure 2 is a vertical sectional view taken on line 2—2 of Figure 1 on a larger scale.

Figure 3 is a partial front-elevation of said aeroplane, likewise shown on a larger scale.

Figures 4 and 5 show sectional views of details of construction on a larger scale than given in Figure 2.

The body 1 of the aeroplane shown may be of any desirable shape and construction and the improved wing 2 may be connected therewith by any suitable means adapted to replace the stay-rods 3 indicated in Figures 2 and 3. The improved wing preferably consists of one or another of the light metals now freely employed in the construction of the different kinds of aircrafts. The wing 2 broadly consists of a flat frame 4, a bottom-layer 5 and a top-layer composed of the outer ends of the jalouzie blades 14. Said frame comprises a head-member, a tail-member and an intermediate part composed of a plurality of hollow slabs 7 of such shape as to form slots 8 between the longitudinal edges of two adjacent slabs, as shown in Figures 2, 4 and 5. These slots are wider at 100

their ends than between them, in order to facilitate the entrance of the air into said slots and its exit therefrom. The lower end of said slots are preferably formed by curved faces which turn the entrances of said slots toward the frontal edge of the wing and approach each other until they merge into the narrowest part of the slots bound by straight faces. The bottom-layer 5 is attached to the underside of the frame 4 to form a distribution chamber 9 and the bottom-layer itself is provided with a plurality of distribution-channels 10 the depth of which decreases toward the rear in a similar manner as the depth of said distribution-chamber. The slabs 7 are carried and kept in their proper place by cross-beams 11 of suitable cross-section. The one end of each beam is supported by the head-member of said frame and the other 20 by the tail-member thereof, which is provided with recesses 12 to reduce the weight of said frame. Vertically over the longitudinal slots 8 a number of supports 13 is arranged on each cross-beam to receive the inner ends of curved jalousie blades 14 which compose the top-layer. The inner end of each jalousie blade is provided with a lateral wing 14', which in conjunction with the jalousie blade proper forms a double-winged 25 deflector 15. The components of these deflectors are joined to form a more or less accented ridge which points downward to the central line of the longitudinal slot beneath it, and are preferably curved to such an extent as to throw one half of two different streams of air, which simultaneously pass through two adjacent longitudinal slots upward, against each other. The outer ends of said jalousie blades are supported by means 30 of distance-pieces 16 preferably of elliptical or similar cross-section to produce outlet-slots 17 considerably greater in width than the longitudinal slots 8. A wing composed of parts such as enumerated above, shaped or 35 spared out to combine the greatest strength with the least weight and properly joined together answers all reasonable requirements.

In order to increase the buoyancy of the aeroplane by means of this improved wing, the frontal edge of the latter is provided with a suitable number of inlet-channels 18 of rectangular, elliptical, oval, circular or of any other cross-section. These inlet-channels are hinged to a shaft 19 preferably embedded in 50 the frontal face of the wing and provided with a lever 20 connected by means of a rod 21 to the upper vertical arm 22 of the arm-cross 23 of the rudder 24, Figures 1 and 2. The object of this arrangement is to keep the 55 inlet-channels 18 under all conditions in a horizontal position to prevent that the air into which the aeroplane forces its way strikes against said inlet-channels at one time from above and at another time from below in an 60 oblique direction, for this would lessen the

volume of air which passes through said inlet-channels. It is therefore necessary to raise the outer ends of said inlet-channels when the aeroplane pursues a downward path and to lower them when it rises, but in both instances said inlet-channels must retain their horizontal position. I may of course employ other means than those shown in order to impart automatically a horizontal position to said inlet-channels. This is of great importance, because the unchanging horizontal position of said inlet-channels assures that the buoyancy of the aeroplane will be always the same, no matter to which a degree the angle of ascension or of descension is altered. This unvarying buoyancy can not be obtained by aeroplanes equipped with so-called slit-wings because they do not permit the air to rush through the slits upward and thereby create useful power when the aeroplane moves along horizontally or when it descends, so that the natural buoyancy thereof can be only improved in the measure the angle of ascension is increased. From the foregoing it will be clear that the carrying-capacity of an aeroplane equipped with a wing constructed in accordance with my present invention will represent a considerable multiple of the carrying-capacity of an aeroplane equipped with a slit-wing of one or the other of the known constructions.

If it is deemed necessary to provide against any emergencies the lever 20 can be extended downwardly to be brought into reach of the pilot. To prevent any leakage of air at the movable connection between the inlet-channels and the distribution-channels the free ends of the latter are provided with a scoop-shaped member 25 each into which a correspondingly shaped member 26 of the corresponding inlet-channel fits. The contacting faces of both members are to this end shaped to the same arc of a circle the centre of which coincides with that of the shaft 19. On the underside of the head-member of the frame 4 a shaft 27 is arranged in close proximity to the shaft 19 and to it is secured at about the deepest part of each distribution-channel 10 a flap 28 adapted to reduce the free cross-sectional area of said inlet-channels 18 at will or shut it off altogether. This is necessary to reduce the buoyancy of the aeroplane during the latter part of a landing flight in order to quickly reduce the velocity of the aeroplane. Said flaps will be fully opened again at a certain height over the landing-place to prevent the formation of whirls on the top-layer which otherwise would tend to let the machine come down to the ground with a hard thud. The simultaneous operation of said flaps is executed by means of a lever 29 secured to said shaft 27 to which lever in turn a rod 30 is linked and extended downward to the pilot-seat, not shown.

To obtain the desired increase in the buoy-

ancy of the aeroplane the improved wing operates as follow:

Since the free ends of the inlet-channels 18 move always in advance of the wave of air created by the frontal edge of the wing when the aeroplane urges its way through the air, and since further these inlet-channels always take up a horizontal position, the edges of their thin walls offer little or hardly any resistance, and the air is thus enabled to pass in its natural state through said inlet-channels 17 and the distribution channels 10 into the distribution chamber 9. Once arrived herein it spreads from said channels 10 laterally throughout the entire length of the distribution chamber and is kept under compression therein by the uninterrupted new supply of air, which compression of course varies in accordance with the velocity of the aeroplane. The compressed air is thus compelled to escape through the longitudinal slots 8 and is thereby thrown upward against the deflectors 15 arranged at a certain distance above the slots 8, which deflectors not only divide the streams of air pressed upward but also bring the streamlets branched off thereby to a collision with each other to form a multitude of powerful air-whirls. The same result would of course be obtained when for instance the deflectors proper were formed by a separate rod of a cross-section similar to an angle-iron to one flange of which the curved jalousie blade might be secured. The powerful whirls created by the collision of the deflected streamlets of air must advance toward the outlet slots 17 with a velocity greater than that of the external air which flows over the exposed parts of the jalousie blades 14 in order to energically take it along with them to rarefy the air on the top-layer of the wing and thus increase the under-pressure. Besides this the accelerated transmission of the air-whirls into the atmosphere is a dire necessity to avoid that the air in the distribution-chamber 9 and in the inlet-channels 18 is compressed to such a degree that the external air is turned aside by the chocked inlet-chamber instead of being permitted to flow freely through them. Until said air-whirls advance from the point of collision to the outlet slots 17 they exert a strong pressure on said jalousie blades and in turn are led by the latter until they pass with a considerable velocity through said outlet-slots. It is of great importance that on leaving said outlet-slots the air-whirls not simply pass tangentially over the exposed part of the next following jalousie blade but strike against it under an angle sufficiently great to scour it to remove any external air therefrom, which when not removed, will favour the formation of whirls in stagnant air so detrimental to the increase of the bouyancy of the aeroplane, as is well known. By means of the greater overpressure and a greater underpressure thus gained

a greater buoyancy as hitherto is obtained and in consequence thereof the carrying-capacity of the aeroplane is increased accordingly.

The deflectors 15, or similar structures adapted to create powerful whirls, as well as the jalousie blades 14 may also be employed on aeroplane-wings in which the air enters into slits or orifices at the underside of the wing and passes upward therethrough, but the actions of both means would in this case be considerably smaller on account of the smaller air pressure.

I claim:

1. An aeroplane-wing comprising a slotted frame, a bottom-layer attached to said frame to form a distribution-chamber, a top-layer composed of jalousie blades arranged on said frame, and means for introducing from the frontal edge of the wing air into said distribution-chamber. 80

2. An aeroplane-wing comprising a slotted frame, a bottom-layer attached to said frame to form a distribution-chamber, a top-layer composed of a plurality of jalousie blades arranged on the upper face of said frame, and inlet-channels adjustably attached to the frontal edge of the wing for introducing air into said distribution-chamber. 90

3. An aeroplane-wing comprising a plane longitudinally slotted frame, a bottom-layer attached to the underside of said frame to form a distribution-chamber, a top-layer composed of curved jalousie blades arranged on the upper face of said frame, and inlet-channels hinged to the frontal edge of the wing for introducing air into said distribution-chamber. 95 100

4. An aeroplane-wing comprising a frame provided with longitudinal slots formed by the opposing edges of hollow members of said frame, a bottom-layer attached to said frame to form a distribution-chamber, distribution-channels arranged in said bottom-layer, a top-layer composed of curved jalousie blades arranged on the upper face of said frame and each separated at its rearward end by discharge slot from the adjacent blade, a plurality of inlet-channels adjustably hinged to the frontal edge of the wing and communicating through said distribution-channels with said distribution-chamber and means for adjusting said inlet-channels simultaneously. 105 110 115

5. An aeroplane-wing comprising a frame consisting of a head member, a tail member and an intermediate part composed of hollow slabs arranged to form longitudinal slots between them; a bottom-layer attached to the underside of said frame to form a distribution-chamber, a plurality of distribution-channels arranged in said bottom-layer, cross-beams arranged on said hollow slabs, supports provided on said cross-beams in line with said longitudinal slots, a top-layer com- 120 125 130

- posed of curved jalousie blades arranged on said frame with their convex side turned upward and provided at their inner ends with deflecting means secured to said supports and 5 at their outer ends with distance-pieces to create discharge slots for the outflowing air, a plurality of inlet-channels adjustably hinged to the frontal edge of the wing, and means for adjusting said inlet-channels simultaneously.
6. An aeroplane-wing comprising a frame consisting of a head member, a tail member and a longitudinally slotted intermediate part; a bottom-layer attached to the underside of said frame to form a distribution-chamber diminishing in depth toward the rear, a plurality of distribution-channels arranged in said bottom-layer, cross-beams on said slotted intermediate part of said frame, 10 supports arranged on said cross-beams vertically over said longitudinal slots, a top-layer composed of a plurality of curved jalousie blades provided at their inner ends with a lateral member in combination with which 15 they form double-winged deflectors the sharp central ridges of which are held by said supports at a convenient distance over the central vertical plain of said longitudinal slots while the outer ends of said curved blades are 20 held apart one from another by distance-pieces to create discharge-slots of greater width than that of the longitudinal slots of said frame, a plurality of inlet-channels adjustably hinged to the frontal edge of the 25 wing in register with said distribution-channels, and means for adjusting said inlet-channels to take up a horizontal position irrespective of the changes in the upward and downward movements of the aircraft.
- 30 7. An aeroplane-wing comprising a frame provided with longitudinal slots wider at both faces of said frame than between said faces, a bottom-layer attached to the underside of said frame to form a distribution-chamber diminishing in depth toward the rear, a plurality of distribution-channels arranged in said bottom-layer and likewise diminishing in depth toward the rear, cross-beams crossing said longitudinal slots and 35 supported by lateral members of said frame, supports arranged on said cross-beams vertically over said longitudinal slots, a top-layer consisting of a plurality of curved jalousie blades provided at their inner ends 40 with double-winger deflectors adapted to divide the streams of air flowing through said longitudinal slots upward and to cause two halves of two adjacent divided streams of air to collide with each other to form air-whirls 45 while the outer ends of said blades are held apart to form discharge-slots for said air-whirls directed by the concave face of the one blade to scour the exposed convex part of the next following blade, inlet-channels adjustably hinged to the frontal edge of the wing 50 in register with said distribution-channels and cooperating with the latter within a bottom part curved concentrically to the axis of rotation of said inlet-channels, means adapted to impart a horizontal position to said inlet-channels when the rudder is manipulated for initiating ascension or descension of the aircraft, means rotatably arranged in the deeper end of each distribution-channel at the rear end of the inlet-channel appertaining thereto to reduce the free sectional area of the latter at will, and means adapted to operate said throttling means simultaneously.
- 55 8. The combination of an aeroplane-body with an aeroplane-wing comprising a frame having an intermediate slotted part, a bottom-layer attached to the underside of said frame to form a distribution-chamber beneath the slotted part of said frame, distribution-channels arranged in said bottom-layer, a top-layer composed of a plurality of curved jalousie blades each adapted to direct outflowing air-whirls to the exposed part of the adjacent rearwardly arranged blade, inlet-channels adjustably hinged to the frontal face of the wing in register with said distribution-channels and adapted to introduce air into said distribution-chamber, means for adjusting said inlet-channels simultaneously, flaps for reducing the free cross-sectional area of said inlet-channels at will, and means for operating said flaps simultaneously.
- 60 9. An aeroplane wing comprising a frame, a bottom layer attached to said frame to form a distribution chamber, a top layer composed of jalousie blades arranged on said frame, and means for introducing air into said distribution chamber.
